(57) **CLAIM**

The ornamental design for a shelving system, as shown and described.

DESCRIPTION

FIG. 1 is a front, bottom perspective view of our shelving system:

FIG. 2 is a rear, bottom perspective view thereof;

FIG. 3 is a front view thereof;

FIG. 4 is a top view thereof;

FIG. 5 is a bottom view thereof;

FIG. 6 is a rear view thereof;

FIG. 7 is a right side view thereof; and,

FIG. 8 is a left view thereof.

The broken line portions of the disclosure are included for the purpose of illustrating environment and form no part of the claimed design.
